SPARK PLUG

John J. Fernandez, Baltimore, Md.

Application June 13, 1945, Serial No. 599,191

10 Claims. (Cl. 123—169)

1

The present invention relates to improvements in spark plugs employed in igniting the charges in internal combustion engines.

All spark plugs now commonly employed have a relatively limited heat range. When, therefore, the operating conditions of the vehicle are changed, it often happens that the previous set of spark plugs run too hot or too cold, and the performance of the engine is seriously affected. When a plug runs too hot the insulator may become heavily coated with oxides, and the firing points may wear rapidly, and in extreme conditions preignition may take place. When the plug runs too cool soot and carbon may deposit on the insulators causing fouling and missing. As an example, a truck or bus, when exchanged from city to highway traffic, may experience the difficulties described above as due to the plugs running too hot. In order to meet these conditions spark plug manufacturers provide a line of plugs in each diameter size to meet the varying running conditions.

The present invention aims to provide a spark plug, which has a relatively large heat range, thereby substantially eliminating the need of changing plugs with varying conditions of operation of the vehicle.

A further object of the present invention is to provide a spark plug, which by reason of its construction and design is self cleaning thereby substantially reducing the possibility of the plug fouling and missing.

To obtain the above ends the plug of the present invention is provided with a constricted mouth providing a Venturi effect at the mouth of the chamber in the plug. The increased speed of the vapors and gases at the mouth of the chamber serves to minimize the deposition of materials on or in the vicinity of the electrodes. The constricted passage and the consequent increased speed of the gases also serve to increase the rate at which the heat is carried away from the sparking zone and from the electrodes.

Further to assist in the performance of the spark plug one of the electrodes is shaped in the form of an annular or curved fork as shown so that it serves to constrict the mouth of the plug and additionally also aids in conducting excessive heat away.

Further objects and advantages of the invention will be understood by persons skilled in the art from the accompanying drawing and the following specification; it being understood that these are illustrative of one embodiment of the invention and that variations thereof falling within the scope of the appended claims will be apparent to persons skilled in the art.

In the drawings:

2

Fig. 1 is an enlarged elevation, partly in section of a plug embodying the invention; and

Fig. 2 is a bottom view of the plug.

In the drawings, the invention is shown embodied in a spark plug having the conventional spark plug central electrode 10 supported by a ceramic insulator 11. The plug barrel 12 and nut 13 grip the insulator 11.

In the present invention, the shape of the mouth or open end of the chamber 14 is constricted. For this purpose the mouth end of the barrel is provided with an annular inwardly directed lip 15 which forms a Venturi throat or mouth as shown. The inner face of the barrel 12 forming the chamber 14 will be seen to have a cylindrical portion 16 and an inwardly convex portion 17, the convex portion extending considerably into the interior and toward the central electrode 10.

The electrode 18 is carried by the barrel mouth portion 15 and consists of the stem 19 and the split ring or fork 20. Each semicircle of the split ring 20 will be seen as tapering off from the stem 19 toward the free ends of the semicircles.

The spark plug embodying the present invention when compared in operation with the conventional spark plug of the same dimensions is found to have a greatly extended heat range without preignition, without fouling and with a general improvement in the operation of the engine. Consequently the same plug can be used either in a high compression or low compression engine, and the same plug can be used in the engine with gasoline of the various grades.

The Venturi effect which causes high velocities of gases adjacent the electrodes aids in preventing overheating of the electrodes, when the engine is operating under heavy load. During idling or light load the Venturi effect is comparatively low, or too low to cause any excessive cooling of the electrodes. It at the same time tends to carry away any solids or liquids that may form in the vicinity of the electrodes and which otherwise would deposit on the electrodes and tend to foul the plug.

The fork electrode 20 also aids during high load to prevent overheating of the plug by carrying the heat away by conduction. Thus, the venturi causes the gases to carry the heat away by conduction and convection and the fork electrode carries it away by conduction. The total effect is that the rate of cooling of the plug is greatest when the engine runs hottest.

The enlarged showing in the drawings indicates the preferred proportioning of the dimensions at the mouth of the plug, although the dimensions and proportions may be varied over a wide range. Generally, the area of the annular space outside the electrode 20 should be substan-

tially greater than the annular space inside the electrode 20. As shown the relationship is roughly two to one, but this may be varied over a considerable range. The tapering of the fork 20 provides for such increased area outside the fork and this also prevents burning off or consumption of the tips of the fork which at the same time provide for high heat conduction to the barrel of the plug and to the cylinder block. The split fork also permits adjustment of the air gap when desired.

As shown the portion 15 is integral with and of the same material as the barrel 12 of the plug. It will be understood, however, that if desired the annular end portion 21 of the barrel (as indicated by the dotted lines) may be made of a more highly heat conductive material such as brass or the like.

What I claim as new and desire to secure by Letters Patent of the United States is:

1. A spark plug having an insulating core, a central electrode carried by said core, a metal shell for said core, an annular lip on the interior face of the shell at its open end and providing a mouth having a minimum diameter in a plane inside the end of the shell, the shell also having an inner zone of enlarged diameter adjacent to said lip on the side away from the mouth of the shell, the central electrode ending in the plane of minimum diameter of the mouth, and a second substantially annular electrode carried by the shell and disposed within the plane of minimum diameter of the mouth, the second electrode encircling the center electrode and dividing the mouth into two annular areas, with the outer annular area substantially greater than the inner annular area.

2. The spark plug of claim 1 in which the annular second electrode is enlarged in the zone of attachment to the shell and is split at the diametrically opposite zone, each half of the annular electrode tapering from the zone of attachment to the split.

3. A spark plug having an insulating core, a central electrode carried by said core, a metallic shell for said core forming an open mouthed chamber with said core, said shell having an annular inwardly directed lip at its mouth, the inner face of said lip having a smoothly flowing curved outline, and a second annular electrode carried by said lip, disposed within the plane of the lip and circumferentially spaced from said lip, the area of the annular space between the second electrode and lip being substantially greater than the area of the annular space between the central and second electrodes.

4. A spark plug having an insulating core, a central electrode carried by said core, a metallic shell for said core forming an open mouthed chamber with said core, said shell having an annular inwardly directed lip at its mouth, the inner face of said lip having a smoothly flowing curved outline, and a second annular electrode carried by said lip, disposed within the plane of the lip and circumferentially spaced from said lip, the area of the annular space between the second electrode and the lip being approximately twice the area of the annular space between the central and second electrodes.

5. A spark plug having an insulating core, a central electrode carried by said core, a metal shell for said core forming an open mouthed chamber with said core, the shell having an integral annular inwardly directed lip at its mouth, a second electrode attached to said lip and hav-

ing two arcuate arms annularly spaced from said lip and from the end of the central electrode, said arms tapering off in cross-section from their attachment points to their free ends, the area of the annular space between the second electrode and the lip being substantially greater than the annular space between the electrodes.

6. A spark plug having an insulating core, a central electrode carried by said core, a metal shell for said core forming an open mouthed chamber with said core, the shell having an integral annular inwardly directed lip at its mouth, a second electrode attached to said lip and having two arcuate arms annularly spaced from said lip and from the end of the central electrode, said arms tapering off in cross-section from their attachment points to their free ends, the area of the annular space between the second electrode and the lip being approximately twice as great as the area of the annular space between the electrodes.

7. A spark plug having an insulating core, a central electrode carried by said core, a metal shell for said core, the shell having an annular lip at its mouth, the shell also having on its inner face a zone of enlarged diameter adjacent to said lip on the side away from the mouth of the shell, a second electrode attached to said lip and having two arcuate arms annularly spaced from said lip and from the end of the central electrode, said arcuate arms having an oblong cross section, the area of the annular space between the second electrode and the lip being substantially greater than the annular space between the electrodes.

8. A spark plug having an insulating core, a central electrode carried by said core, a metal shell for said core, the shell having an annular lip at its mouth, the shell also having on its inner face a zone of enlarged diameter adjacent to said lip on the side away from the mouth of the shell, a second electrode attached to said lip and having two arcuate arms annularly spaced from said lip and from the end of the central electrode, said arcuate arms having an oblong cross section, the area of the annular space between the lip and the second electrode being approximately twice the area of the annular space between the electrodes.

9. A spark plug having an insulating core, a central electrode carried by said core, a metal shell for said core, the shell having an annular lip at its mouth, the shell also having on its inner face a zone of enlarged diameter adjacent to said lip on the side away from the mouth of the shell, a second electrode attached to said lip and having two arcuate arms annularly spaced from said lip and from the end of the central electrode, the area of the annular space between the second electrode and the lip being substantially greater than the annular space between the electrodes.

10. A spark plug having an insulating core, a central electrode carried by said core, a metal shell for said core, the shell having an annular lip at its mouth, the shell also having on its inner face a zone of enlarged diameter adjacent to said lip on the side away from the mouth of the shell, a second electrode attached to said lip and having two arcuate arms annularly spaced from said lip and from the end of the central electrode, the area of the annular space between the lip and the second electrode being approximately twice the area of the annular space between the electrodes.

JOHN J. FERNANDEZ.
